UNITED STATES PATENT OFFICE.

MILO G. KELLOGG, OF CHICAGO, ILLINOIS.

TELEPHONE-EXCHANGE SYSTEM.

No. 804,862.

Specification of Letters Patent.

Patented Nov. 21, 1905.

Application filed December 20, 1894. Serial No. 532,483.

To all whom it may concern:

Be it known that I, MILO G. KELLOGG, a citizen of the United States, residing at Chicago, in the county of Cook and State of Illinois, have invented certain new and useful Improvements in Telephone-Exchange Systems, of which the following is a specification.

The invention especially relates to a system in which the lines are metallic circuits; and the invention consists in a system of calling, answering calls, switching, testing, and clearing out, all of which I will describe in detail.

In the accompanying drawings, Figure 1 shows a divided exchange system and illustrates two divisions of boards with two boards in each division and the circuit connections and apparatus at the central office for two subscribers' lines. Fig. 2 shows the plugging switching apparatus of the central-office operator; Fig. 3, the central-office-operator's test devices, and Fig. 4 the organization at the subscriber's station.

Fig. 1 shows two divisions of boards (A and B) of two boards in each division (A' A² and B' B²) for two divisions of lines A and B. Each line has a switch on each board of its division of boards and on one board of the other division of boards, according to my divided exchange system. The switches are represented at s s, &c. Each switch has two contact-pieces (marked g j) and a switch-hole (marked l) adapted to receive a loop switch-plug, (marked D D in Fig. 2,) and when a plug is inserted into a switch-hole its two contact-pieces form connection with the two contact-pieces g and j of the switch, respectively. One side or branch of a line is connected to one contact-piece of each switch of the line—say piece g—and the other side or branch of the line is connected to the other contact-piece of each switch of the line—say j.

There are two annunciators for each line (marked w w) and two retardation-coils for each line, (marked x x.) One side or branch of each line is permanently grounded through one annunciator and retardation-coil of the line, and the other side or branch of the line is permanently grounded through the other annunciator and retardation-coil of the line.

The two annunciators of a line are placed at two boards one at each division of boards and at boards where the calls of the line are to be answered.

Fig. 2 shows an operator's cord system for an operator at any board. D D are a pair of

loop-plugs, each adapted to be placed in any switch s at its board and when so placed to connect its contact-pieces with the two contact-pieces g j of the switch, respectively. The two contact-pieces of one plug are connected to the two contact-pieces of the other plug, respectively, by two flexible switch-conductors. Each operator has as many pairs of plugs with cords as she may need for her work.

Y is a looping-in switch for the pair of plugs shown, having two switch-levers and three pairs of contact-bolts on which the levers may be alternately placed. The two levers of the switch are connected to the two flexible conductors, respectively, which connect the plugs.

t is the operator's telephone, and C is a test-battery. The telephone and battery are in a loop which connects a pair of the switch-bolts.

v is a clearing-out annunciator, and C² is a test-battery. This annunciator and the battery are in a loop which connects another pair of the switch-bolts.

C is a calling-generator in a loop, which connects the remaining pair of switch-bolts.

Each pair of plugs has a switch Y, a clearing-out annunciator v, and a test-battery C².

In the operator's test system, T is a test-plug, and t' a test-receiving instrument. The plug is adapted to be placed for testing into connection with any switch-contact g or j at its board and is grounded through the test-receiving instrument. Each operator has a test system.

In the subscriber's station apparatus, (shown in Fig. 4,) 1 is the telephone-switch; 2, the subscriber's telephone; 3, his signal-bell, and 4 his calling-generator. a and b are two keys each having a pair of contacts normally open, but closed at the will of the subscriber. The circuits and connections are substantially as shown and may be such as are usual in subscriber's station apparatus with the addition of the connections of the keys, such as will be described.

When the telephone is on the switch, the signal-bell is in the circuit of the line and the telephone is short-circuited, so as to be practically out of the circuit. When the telephone is off the switch, it is in the circuit of the line and the signal-bell is short-circuited, so as to be practically out of the circuit. The armature of the calling-generator is in the circuit of the line when the generator is operated.

One point of each of the two keys a and b

is grounded. The other point of key *a* is connected to the line-circuit on one side of the generator-armature coil, and the other point of the key *b* is connected to the line-circuit 5 on the other side of the armature.

The subscriber's station apparatus should preferably be connected into the line-circuit, so that the generator is between key *a* and the annunciator of the line which is located 10 in division A of boards and is between key *b* and the annunciator of the line which is located 15 in division B of boards.

The annunciators may all be of the ordinary kind of non-polarized telephone-annunciators.

15 The operation of the system is as follows: If a subscriber wishes connection with a subscriber whose line is in division A, he presses on his key *a* and operates his generator. A calling-current then goes through a circuit 20 from the subscriber's ground through the contacts of key *a*, the generator, one side or branch of the line, and to ground at the central office through the annunciator located at one of the boards of division A. The annunciator 25 will thereby indicate a call. The other annunciator of the line will not indicate a call, because the line is grounded between the generator and the annunciator by a circuit connection through key *a* of practically no 30 resistance and the annunciator is practically short-circuited. When the operator to whom the annunciator which indicates the call is assigned observes the indication, she places one of her switch-plugs D in the switch of the line, 35 the levers of the switch Y being in position so that her telephone bridges or cross-connects the conductors of the plug, her telephone is in closed circuit with the line and she will receive the order of the subscriber. This closed circuit 40 is, say, from one side or branch of the line through the plug contact-piece connected with it, to the flexible conductor connected with the plug contact-piece, thence to the switch-lever, thence through the telephone to 45 the other switch-lever, thence to the other contact of the plug, and thence to the other side or branch of the line. When the operator receives the order of the subscriber, she 50 tests the line wanted, as will hereinafter be indicated, and if she finds it to be free, or not in use, she places the other plug of the pair in the switch of the line. The two lines are then connected together into a closed metallic circuit, and this circuit is bridged or cross-connected 55 by the operator's telephone. This closed metallic circuit is, say, from one side or branch of one line to the contact-piece of the plug in its switch, thence through one of the flexible conductors to a contact-piece of 60 the plug, which is in the switch of the other line, thence to one side or branch of the other line, thence through the circuit of that line to the other contact-piece of the plug, which is in its switch, thence through the other flexible conductor to the other contact-piece of the 65

first-mentioned plug, and thence to the other side or branch of the first-mentioned line. The operator may now move the lever of the looping-in switch Y, so that the calling-generator B bridges the two sides of the closed metallic circuit, and a calling-current will pass over the metallic circuit to the line of the subscriber wanted and ring his signal-bell. The operator will then move the levers of the switch, so that the clearing-out annunciator 70 75 *v* bridges or cross-connects the closed metallic circuit of the two lines. The subscribers will then carry on their conversation. When the subscribers are through conversation, either may operate his calling-generator without pressing on either of his keys *a* or *b*. A current will then pass through his metallic circuit, which will operate the clearing-out annunciator in the central office, which bridges or connects the two sides or branches of his 80 line. 85

If the subscriber from whom the call had originated had desired conversation with a subscriber whose line is in division B, the operations would have been the same as those 90 described except that he would have pressed on key *b* when he sent in his call.

When two lines are connected together into a closed metallic circuit for conversation, one side of the circuit is grounded at the central office through one annunciator and retardation-coil of each line and the other side of the circuit is grounded through the other annunciator and retardation-coil of each line. The high retardation and resistance of these ground 95 connections or taps are, however, such as not to greatly affect the telephone conversation 100 between the subscribers.

It is evident that when a clearing-out signal 105 is sent by either subscriber, as heretofore described, a portion of the generated current will divide so as to pass through the line-annunciators of the two lines. On account of the high resistance of the circuits through the annunciators the amount of current which 110 passes through them will not be sufficient to operate them. The circuit through the clearing-out annunciator will be of much less resistance, and consequently much more current 115 will pass through it and sufficient to operate it. The strength of the generator and the resistances of the circuits and apparatus and the sensitiveness of the annunciators can be readily 120 adjusted to each other in such a manner that when a call is sent in by a subscriber it will operate the annunciator he intends and will not operate his other annunciator, and when a clearing-out current is sent by either subscriber it will operate the clearing-out annunciator and will not operate either of the line- 125 annunciators.

Should any subscriber attempt to send a call for a connection by pressing either of his keys and operating his calling-generator while his line is already switched for conversation, as 130

may be the case when the subscribers neglect to send a clearing-out signal when they are through conversation or the disconnection is not promptly made by the operator, part of the current generated will pass through his line-annunciators, and part of the current will also pass through the line-annunciators of the other subscriber if the two lines are connected together. The greater portion of the current will, however, pass through the clearing-out annunciator. The strength of the generators and the resistances of the circuits and apparatus and the sensitiveness of the annunciators can be readily and should be adjusted to each other in such a manner that when a call is sent in by a subscriber and his line is already switched enough of the current will not pass through any of the line-annunciators to operate them; but sufficient current will pass through the clearing-out annunciator to operate it. When the operator moves the levers of his switch Y so as to connect her calling-generator B into circuit, the generator is bridged between the two sides of the combined circuit of the two lines, and the current divides, according to the well-known law of the distribution of currents in derived circuits, so that the greater part of the current passes in two derived circuits to the two subscribers' stations, respectively, and operates their call-bells, whereas by far the smaller portion of the current will pass through the line-annunciators, but will not operate them, because the amount of current is too small. By well-known modifications of the operator's switches the line from which the call originates may be disconnected from the generator while the operator sends the calling-current, and in that case the current will only go over the line and through the annunciators of the subscriber wanted. In either case the strength of the operator's generator and the resistances of the circuits and apparatus and the sensitiveness of the bells and the annunciators can be readily and should be adjusted to each other in such a manner that when a call is sent by the operator the line-annunciators will not be operated, while the subscribers' bells (or the subscriber's bell, as the case may be) will be rung by the current. The system may be modified—as, for instance, for multiple switchboard systems, which do not contain the divided-exchange feature—by leaving out the annunciator with its ground connection, which is connected to one side or branch of the line. In that case the key of the subscriber's station, which is to be depressed to operate this annunciator, may be left out. The line-annunciators, as well as the clearing-out annunciator, will be in closed circuit with the generator when the clearing-out signal is sent, and in all cases the strength of the current and the resistances of the line-annunciator circuits should be so great as compared with the resistance of the clearing-out annunciator.

ciator-circuit that when the clearing-out current passes through them the line-annunciator will not be operated.

The system of switching and operation which I have herein described may be modified so as to prevent in other ways the line-annunciators from being operated while the line is switched and either a subscriber or an operator sends a calling-current over the line.

The test system is as follows: When a line is switched for conversation, it has a test-battery, either the battery C' in the loop with the operator's telephone or the battery C^2 in the loop with the clearing-out annunciator, in a bridge or cross connection to the two sides of the line. When, therefore, an operator at any board places her test-plug T into contact with any contact-piece g or j of a line and the line is switched for conversation, a complete circuit is established which contains her test-receiving instrument and a test-battery, and the instrument will sound or respond, indicating that the line is switched for use. The complete circuit is, say, from ground through the test-receiving instrument to the test-plug, thence to the switch-contact connected with one side of the line to which the plug is applied, thence to the switch-contact of the line at which the line is switched, thence through the test-battery, which bridges the circuit to the other side of the line, and thence to ground through the annunciator and retardation-coil, through which the last-mentioned side of the line is grounded.

When a line is not switched for conversation, there is no complete circuit established on testing which contains the operator's test-receiving instrument and a battery, and the instrument will not sound. The operator can therefore determine by testing whether or not any line connected to her board is switched for conversation.

Instead of the annunciator and retardation-coil for each line an annunciator of high resistance and retardation to telephone-currents may be used.

Other systems of testing than that shown and described may be used in connection with the calling and switching system I have described.

I claim as my invention—

1. In a telephone-exchange system, the metallic-circuit lines divided into two divisions, the multiple switchboards, divided into two divisions, one division of boards for each division of lines; switches for each of said lines, one switch for each line on each of the several boards of its division, and on one board of the other division; two annunciators at the central office for each line, through one of which one side or branch of the line is permanently grounded and through the other of which the other side or branch of the line is permanently grounded; in combination with a calling-generator at each subscriber's sta-

tion permanently or whenever operated to send a call in the through or closed circuit of the line at said station, and contacts to at will ground his line on either side of said generator.

- 5 2. In a telephone-exchange system, the metallic-circuit lines divided into two divisions, the multiple switchboards divided into two divisions, one division of boards for each division of lines, switches for said lines, one switch for each line on each board of its division and on one board only of the other division, each switch having two contact-pieces, one branch of each line being connected to one of the contact-pieces of each switch 15 of the line and the other branch of the line being connected to the other contact-piece of each switch of the line, in combination with two permanent ground connections at the central office for each line, two annunciations for 20 each line, one in each of the ground connections and at a board in each division of boards and where the line has a switch, pairs of loop switch-plugs at each board, the two contacts of each plug being connected by flexible conductor-circuits to the two contacts of its mate, 25 respectively, each plug being adapted to be inserted into each switch at its board and when inserted to form contact between its two contacts and the two contact-pieces of the switch, 30 respectively, a calling-generator at each subscriber's station permanently or whenever operated to send a call in the through or closed circuit of the line at said station, and contacts at each subscriber's station to at will ground 35 the line on either side of the generator.

3. In a telephone-exchange system, the metallic-circuit lines divided into two divisions, the multiple switchboards divided into two divisions, one division of boards for each division of lines, switches for said lines, one switch for each line on each board of its division and on one board only of the other division, each switch having two contact-pieces, one branch of each line being connected to one of the contact-pieces of each switch of the line and the other branch of the line being connected to the other contact-piece of each switch of the line, in combination with two permanent ground connections at the central office for 40 each line, two annunciations for each line, one in each of the ground connections and at a board in each division of boards and where the line has a switch, pairs of loop switch-plugs at each board, the two contacts of each 45 plug being connected by flexible conductor-circuits to the two contacts of its mate, respectively, each plug being adapted to be inserted into each switch at its board and when inserted to form contact between its two contacts and the two contact-pieces of the switch, 50 respectively, clearing-out annunciations, one for each pair of plugs, in a bridge or cross connection to their two flexible conductor-circuits, a calling-generator at each subscriber's 55 station permanently or whenever operated to

send a call in the through or closed circuit of the line at said station, and contacts at each subscriber's station to at will ground the line on either side of the generator.

4. In a telephone-exchange system, a metallic-circuit line extending from its subscriber's station to the central office, and two annunciations at the central office for such line, through one of which one side or branch of the line is permanently grounded, and through the other 70 of which the other side or branch of the line is permanently grounded, in combination with a calling-generator permanently or whenever operated to send a call in the through or closed circuit of the line at the subscriber's station 75 and two keys there, each with a pair of contacts normally open but closed at the will of the subscriber, one contact of each key being grounded and the other two contacts of the keys being connected to the line-circuit, one 80 on one side and the other on the other side of the generator.

5. In a telephone-exchange system, metallic-circuit lines extending from the subscriber's station to the central office, and two annunciations at the central office for each line, through one of which one side or branch of the line is grounded and through the other of which the other side or branch of the line is grounded, in combination with a calling-generator permanently or whenever operated to send a call in the through or closed circuit of the line at the subscriber's station, two keys there, each with a pair of contacts normally open but closed at the will of the subscriber, one contact of each key being grounded and the other two contacts of the keys being permanently connected to the line-circuit, one on one side and the other on the other side of the generator, and switching apparatus at the central 90 office to connect together any two of the lines into a metallic circuit which does not contain the line-annunciator.

6. In a telephone-exchange system, two metallic-circuit lines temporarily connected together into a closed metallic circuit for conversation, and two annunciations for each line, through which, respectively, the two sides of said metallic circuit are grounded in four ground connections, two from each side of the circuit, in combination with a clearing-out annunciator in a bridge or cross-connecting circuit to said closed metallic circuit, and a calling-generator operated in said circuit at either subscriber's station to send a clearing-out signal, the strength of the generator, the resistances of the various apparatus, and circuits, and the sensitiveness of the annunciations being such that when the generator is thus operated, the line-annunciations will not be 110 operated while the clearing-out annunciator will be operated by the current passing through them.

7. In a telephone-exchange system, two metallic-circuit lines temporarily connected to-

gether into a closed metallic circuit for conversation, and two annunciators for each line, through which, respectively, the two sides of said metallic circuit are grounded in four ground connections, two from each side of the circuit, in combination with a clearing-out annunciator in a bridge or cross-connecting circuit to said closed metallic circuit, and a calling-generator operated in said circuit at either subscriber's station to send a clearing-out signal, said line-annunciators not being operated but said clearing-out annunciator being operated by the current generated.

8. In a telephone-exchange system, two metallic-circuit lines temporarily connected together into a closed metallic circuit for conversation, and four annunciators through which, respectively, the two sides of said metallic circuit are grounded in four ground connections, two from each side of the circuit, in combination with a clearing-out annunciator in a bridge or cross-connecting circuit to said closed metallic circuit, and a calling-generator operated in said circuit at either subscriber's station to send a clearing-out signal, the strength of the generator, the resistances of the various apparatus and circuits, and the sensitiveness of the annunciators being such that when the generator is thus operated, the line-annunciators will not be operated while the clearing-out annunciator will be operated by the current passing through them.

9. In a telephone-exchange system, two metallic-circuit lines temporarily connected together into a closed metallic circuit for conversation, and four annunciators through which, respectively, the two sides of said metallic circuit are grounded in four ground connections, two from each side of the circuit, in combination with a clearing-out annunciator in a bridge or cross-connecting circuit to said closed metallic circuit, and a calling-generator operated in said circuit at either subscriber's station to send a clearing-out signal, said line-annunciators not being operated, but said clearing-out annunciator being operated by the current generated.

10. In a telephone-exchange system, two metallic-circuit lines temporarily connected together into a closed metallic circuit for conversation, and two annunciators for each line, through which, respectively, the two sides of said metallic circuit are grounded in four ground connections, two from each side of the circuit, in combination with a clearing-out annunciator, in a bridge or cross-connecting circuit to said closed metallic circuit, a calling-generator operated in said circuit at either subscriber's station and a key then operating to ground said circuit at said station on one side of said generator, the strength of the generator, the resistances of the various apparatus and circuits, and the sensitiveness of the annunciators being such that when the generator is thus operated, the line-annuncia-

tors will not be operated while the clearing-out annunciator will be operated by the current passing through them.

11. In a telephone-exchange system, two metallic-circuit lines temporarily connected together into a closed metallic circuit for conversation, and two annunciators for each line, through which, respectively the two sides of said metallic circuit are grounded in four ground connections, two from each side of the circuit, in combination with a clearing-out annunciator in a bridge or cross-connecting circuit to said closed metallic circuit, a calling-generator operated in said circuit at either subscriber's station and a key then operating to ground said circuit at said station on one side of said generator, said line-annunciators not being operated but said clearing-out annunciator being operated by the current generated.

80 12. In a telephone-exchange system, two metallic-circuit lines temporarily connected together into a closed metallic circuit for conversation, and two annunciators, through which, respectively, the two sides of said metallic circuit are grounded, in combination with a clearing-out annunciator in a bridge or cross-connecting circuit to said closed metallic circuit, a calling-generator operated in said closed metallic circuit at either subscriber's station and a key then or while the generator is thus being operated in said closed metallic circuit operating to ground said circuit at said station on one side of said generator, said line-annunciators not being operated but said clearing-out annunciator being operated by the current generated.

85 13. In a telephone-exchange system, two metallic-circuit lines temporarily connected together into a closed metallic circuit for conversation and a line-annunciator through which one side of said metallic circuit is then grounded, in combination with a clearing-out annunciator in a bridge or cross-connecting circuit to said closed metallic circuit, a calling-generator operated in said closed metallic circuit at either subscriber's station to send a clearing-out signal, and a key then or while the generator is thus being operated in said closed metallic circuit operating to ground said circuit at said station on one side of said generator and with said generator between said ground connection thus established and said annunciator, the strength of the generator, the resistances of the various apparatus and circuits, and the sensitiveness of the annunciators being such that when the generator is thus operated the line-annunciator will not be operated, while the clearing-out annunciator will be operated by the current passing through them.

14. In a telephone-exchange system, two metallic-circuit lines temporarily connected together into a closed metallic circuit for conversation and a line-annunciator through which

one side of said metallic circuit is then grounded, in combination with a clearing-out annunciator in a bridge or cross-connecting circuit to said closed metallic circuit, a calling-generator operated in said closed metallic circuit at either subscriber's station to send a clearing-out signal, and a key then or while the generator is thus being operated in said closed metallic circuit operating to ground 5

10 said circuit at said station on one side of said generator and with said generator between

said ground connection thus established and said annunciator, said line-annunciator not being operated but said clearing-out annunciator being operated by the current generated.

In testimony whereof I have hereunto subscribed my name.
